UNITED STATES PATENT OFFICE.

MARCUS GARFINKEL, OF DETROIT, MICHIGAN.

SAFE.

1,347,693.

Specification of Letters Patent.

Patented July 27, 1920.

Application filed February 13, 1920. Serial No. 358,540.

To all whom it may concern:

Be it known that I, MARCUS GARFINKEL, a citizen of Russia, residing at Detroit, in the county of Wayne and State of Michigan, have invented certain new and useful Improvements in Safes, of which the following is a specification, reference being had therein to the accompanying drawings.

This invention relates to safes, vaults, and safe deposit receptacles and has special reference to that class of safes ordinarily used in offices and private residences.

The primary object of my invention is to furnish a safe of the above class with shiftable compartments that are concealed within the safe under normal conditions, so that should the doors of the safe be blown off or surreptitiously opened by burglars or others not familiar with the safe, it will appear as though empty and in all probability mislead those attempting to obtain valuables from the safe. Associated with the shiftable compartments are shiftable fenders that close the main chamber of the safe when the compartments therein are concealed and novel means articulates the fenders and shiftable compartments so that there will be a movement in synchronism when said operating means is brought into action to shift the compartments in a desired direction.

Another object of this invention is to provide a safe with inner and outer doors, the outer door having a novel locking mechanism which must be actuated before access can be had to the inner door, and the inner door contains mechanism for shifting compartments within the safe and the mechanism must be actuated before the outer door is opened.

A further object of my invention is to provide a safe having inner and outer doors equipped with mechanisms which must be successively operated, otherwise it is impossible to reach the secret compartments within the safe.

A still further object of my invention is to provide a safe wherein the parts are constructed with a view of reducing the cost of manufacture and at the same time retain those features by which durability and ease of assembling are secured. With such ends in view, my invention resides in the novel

construction to be hereinafter considered and then claimed and reference will now be had to the drawings, wherein—

Figure 1 is a front elevation of the safe showing the doors thereof partly broken away and partly in section;

Fig. 2 is a vertical longitudinal sectional view of the same;

Fig. 3 is a horizontal sectional view of the same;

Fig. 4 is a vertical transverse sectional view of a portion of the safe, showing the inner door as partly broken away and partly in section, and

Fig. 5 shows detail sectional views of permutation locks or operating devices forming part of the same.

In describing my invention by aid of the views above referred to, I desire to point out that the same are intended as merely illustrative of an example whereby my invention may be put into practice, and I do not care to confine myself to the precise construction or arrangement of parts shown, other than as defined by the appended claims.

In the drawings, the reference numeral 1 denotes a rectangular safe body that may be a solid mass or fabricated from structural steel, concrete, fire proof material or any material which will lend or contribute to safety of valuables placed within the body. In the body 1, closer to the rear wall thereof than the front wall, is a chamber 2 which is also rectangular and has its top and bottom walls provided with rails or tracks 3 for the casters or trucks 4 of shiftable vertically disposed compartments 5, 90 said compartments being movable to and from each other and of such size as to occupy end portions of the chamber 2, as best shown in Fig. 3. The compartments 5 may be constructed of sheet metal or a suitable material and each compartment may be provided with drawers 6, pigeon holes, shelves, or any divisional construction for the reception of valuables. The compartments 5, when in inactive position are concealed behind vertical front walls 7 in the chamber 2 and said compartments are constructed of a size compared to the chamber 2, to occupy the central portion of said chamber

when in an active position, whereby easy access can be had to the drawers 6 of the compartments. The compartments 5 are furthermore constructed so that the confronting or exposed walls thereof will be similar to the rear wall of the chamber 2, and with the compartments 5 in inactive position, as shown in Fig. 3, said compartments will serve as movable side walls for the central portion of the chamber 2, and viewing said chamber from the doorway of the safe, it will be impossible to detect the compartments 5 other than as forming the central chamber in the safe body 1.

15 The front wall of the safe body 1 has an inner beveled doorway 8 for a hollow inner door 9, which is hinged in the doorway 8. The inner doorway 8 communicates with an outer stepped or chamfered doorway 11 provided with a stepped hollow door 12, which is hinged to the front wall of the safe body 1, as at 13. Before describing the inner and outer doors, it is thought best to again refer to the shiftable compartments 5 and the manner in which said compartments are articulated for movement in synchronism.

At the front of the chamber 2 and centrally of the inner doorway 8 is a vertically disposed center bar 14 and movable to and from this center bar, in front of the partitions 7, are fenders or gratings 15 constructed so as to be ornamental and at the same time prevent the hands from being inserted through the fenders into the chamber 2 of the safe. The reciprocable fenders 15 have the upper and lower ends thereof provided with rollers or wheels 16 movable on rails 17 set in the top and bottom walls of the chamber 2, and the outer vertical edges of said fenders, adjacent the upper and lower ends thereof, are connected to sprocket chains or flexible members 18 extending into auxiliary chambers 19 in the safe body 1.

40 The chambers 19 are parallel with the side walls of the chamber 2 and are adjacent the top and bottom walls of said chamber. In the chambers 19 are sprocket wheels 20 over which the sprocket chains 18 are trained, said sprocket chains having the ends thereof attached to the outer side walls of the compartments 5, so that when said compartments are shifted, to an active position the fenders 15 are moved away from the center bar 14 to an open position, thus permitting of easy access being had to the drawer 6 of the compartments 5.

45 The center bar 14 and the rear wall of the chamber 2 coöperate in supporting rotatable shafts 21 in superposed relation centrally of the chamber 2, and on these shafts are drums 22 connected by chains 23 or flexible members to the confronting walls of the compartments 5, and when the shafts 21 are rotated the chains 23 are wound on

the drums 22 to pull the compartments 5 toward each other, and through the medium of the sprocket chains 18, open the fenders 15.

50 The forward or outer ends of the shafts 21 terminate in shanks 24 adapted to fit in sockets 25 forming part of the hub portions of sprocket wheels 26 rotatably supported in the hollow inner door 9.

55 Journaled in the inner door 9, centrally thereof, is a socket member 27 having a double sprocket wheel 28 and a large ratchet wheel 29. Trained about the double sprocket wheel 28 and the sprocket wheels 26 are endless sprocket chains 30 and it is 80 through the medium of these sprocket chains that the shafts 21 can be rotated when rotative movement is imparted to the socket member 27. About the socket member 27, between the double sprocket wheel 28 and the ratchet wheel 29, is a spiral band spring 31, which has the inner convolutions thereof attached to the socket member, and the outer convolutions thereof attached to the rear wall of the inner door, as at 32, and 90 the retractile force of this spring is adapted to impart movement to the socket member 27, so that the compartments 5 will be shifted to active positions. This is automatically accomplished when the socket member 27 is released by a pivoted pawl 33 engaging the ratchet wheel 29. This is best shown in Fig. 4, and again referring to Fig. 2 it will be noted that the pawl 33 is carried by a socket member 34 journaled in the walls of 100 the inner door 9. The socket member 34 is adapted to receive the shank of a latch member 35 carried by the central bar 14 and said latch member is adapted to lock the fenders 15 in engagement with each other. Since the pawl 33 and the latch member 35 will be moved in synchronism by the socket member 34, it is obvious that the fenders 15 can be simultaneously released with the ratchet wheel 29, thus permitting the spring 31 to shift the compartments 5 to an active position. 110

115 Mounted in the outer hollow door 12 is a partition 36 and slidable between this partition and the inner wall of the door are transversely disposed locking plates 37, said locking plates being arranged at the top and bottom edges of the door so as to extend into grooves 38 in the safe body 1 and thus firmly lock the outer door when closed. 120 The locking plates 37 are guided on rods 39 suitably mounted between the partition 36 and the inner wall of the outer door 12; and on the rods 39 are coiled expansion springs 40 which assist in supporting the locking plates, particularly the uppermost plates, and permit of the locking plates being easily shifted to locked positions in the grooves 38 of the safe body.

125 The inner edges of the locking plates 37 130

are provided with bifurcated lugs 41 and pivotally mounted in said bifurcated lugs are levers 42 having ends thereof pivotally supported, as at 43, on the inner wall of the outer door 12. The opposite ends of said levers are pivotally connected to rack bars 44 movable against rollers 45 and retained in mesh with a pinion 46 common to both of said rack bars. The pinion 46 is carried by the hub portion of a cross head 47 between the partition 36 and the outer wall of the door 12, said cross head having its hub portion journaled in the partition 36. Reciprocable in the hub portion of the cross head 47 is a pin 48, the inner end of which is adapted to enter the socket member 27 of the inner door and rotate said socket member when the reciprocable pin 48 is pushed inwardly and rotated. To hold the pin 48 in a retracted or extended position, a coiled spring 49 encircles said pin within the cross head 47 and the hub portion thereof, and with said pin protruding from the door 12 and provided with a hand piece 50, it is possible to easily manipulate said pin.

The cross head 47 is adapted to be locked against rotation by spring pressed reciprocable members 51 arranged in guide brackets 52, carried by the partition 36, said reciprocable members being pressed by coiled springs 53 at the outer ends thereof. Journaled in the front wall of the outer door 12 and the partition 36 thereof are the arbors 54 and 55 of permutation devices or locks including knobs 56, and dials 57. Any well known type of permutation mechanism can be used and forms no part of this invention other than affording a locking means for the arbors 54 and 55. This construction is best shown in Figs. 1 and 5 where it will be noted that the inner ends of the arbors 54 and 55 have cam members 58 extending into the reciprocable members 51 to hold said members against accidental movement, and the cams 58 may be properly shifted by the arbors 54 and 55 to release the reciprocable members 51.

Loose on the arbor 55 is a sleeve 59 having a crank handle 60 at the outer end thereof. The inner end of the sleeve 59 has a sprocket wheel 61, a shifting disk 62 and a shifting finger 63.

On the arbor 54 is a loose sprocket wheel 64 having an integral shifting disk 65, and these two last mentioned elements are in a vertical plane with the sprocket wheel of the arbor 55 so that an endless sprocket chain 66 may be trained over the sprocket wheels 61 and 64.

After the arbors 54 and 55 have been properly rotated to cause the cams 58 to release the reciprocable members 51, said reciprocable members may be shifted to release the cross head 47 by rotating the sleeve 59 which through the medium of the sprocket

wheels 61 and 64, sprocket chain 66, and shifting disks 62 and 65 cause the reciprocable members 51 to be retracted.

On the inner side of the front wall of the outer door 12 are vertical guides 67 for a pin locking plate 68, said plate having an opening 69 providing clearance for the reciprocable pin 48, when said plate is raised, otherwise, the plate 68 extends behind an annular shoulder 70 of the reciprocable pin 48 and prevents said pin from being pushed inwardly to enter the socket member 27. The pin locking plate 68 is normally retained in a lowered position by a spring 71 pressing on the upper edge thereof, and in order that said plate may be raised it has a side extension 72 adapted to be engaged by the finger 63 of the sleeve 59 on the arbor 55.

The inner door 9 has a conventional form of lock 73, as best shown in Fig. 4.

To successfully open the safe, without injuring any parts thereof, it is necessary that the permutation devices be properly actuated in order that the cams 58 thereof will release the reciprocable members 51. After this has been accomplished, the crank or handle 60 may be operated to rotate the disks 65 in synchronism and cause the reciprocable members 51 to be retracted in the guides 52 against the expansive force of the springs 53. Simultaneous with this operation the finger 63 raises the pin locking plate 68 and the reciprocable pin 48 may now be manipulated. The pin 48 may be rotated through the medium of the hand piece 50 and the pinion 46 will shift the rack bars 44 and move the levers 42 so that the locking plates 37 will be retracted against the action of the springs 40, thus releasing the upper and lower edges of the outer door 12 so that said door may be swung on its hinges 13 to an open position. However, before the outer door is opened, it is necessary for the socket member 34 to be turned to elevate the pawl 33 and release the retractile force of the spring 31 and the compartments 5 will be shifted to an active position. With the fenders 15 open access may be had to the drawer 6 in said compartments.

As soon as the compartments 5 have been shifted to active positions the inner door 9 can be unlocked and swung on its hinges so that access may be had to said compartments.

It is thought that the operation of closing the safe will be apparent without further description, and it is obvious that some of the features of my invention may be embodied in safes constructed other than disclosed in the accompanying drawings.

What I claim is:

1. A safe comprising a body having a chamber therein, shiftable compartments in

- the chamber of said safe body and movable to and from each other, a door for the safe; and means carried by said door adapted for shifting said compartments, 5 said means including a reciprocable and rotatable pin for moving said compartments away from each other and a spring for moving said compartments toward each other.
- 10 2. A safe as characterized in claim 1, wherein the compartments are concealed at the sides of the body chamber when in inactive position, and fenders adapted to close said body chamber.
- 15 3. A safe comprising a body having a chamber therein, reciprocable fenders closing said body chamber, shiftable compartments in said body chamber, means connecting said fenders and compartments for 20 movement together, and means adapted for moving said compartments and fenders.
4. A safe comprising a body having a chamber therein, fenders closing said body chamber, an inner door carried by said safe 25 body, an outer door carried by said safe body, means in said inner door for opening said fenders, and means in said outer door for operating the means of said inner door.
5. A safe as characterized in claim 4, 30 wherein the means of said inner door includes flexible members and a spring, and the means of said outer door includes a reciprocable and rotatable pin.
6. A safe comprising a body, shiftable 35 compartments therein, an inner door carried by said safe body, an outer door carried by said safe body, means in said inner door adapted for shifting said compartments

ments, and means in said outer door adapted for operating the means of said inner door. 40

7. A safe as characterized in claim 6, wherein the means of said inner door includes sprocket wheels and chains, and the means of said outer door includes a rotatable pin. 45

8. A safe comprising a body having a chamber therein, shiftable compartments normally concealed in the sides of said chamber, means connecting the confronting walls of said compartments adapted for 50 moving said compartments toward each other, means connecting the outer walls of said compartments adapted for moving said compartments away from each other, a door for the chamber of said safe body, and 55 means carried by said door adapted for operating said chamber moving means.

9. A safe comprising a body having a chamber therein, shiftable compartments in said chamber and adapted to be concealed 60 therein, an inner door for said body chamber, an outer door for said body chamber, means carried by said inner door, and operable only when said door is closed for shifting the compartments in said body 65 chamber, and means carried by said outer door and operable only when said door is closed for actuating the means of said inner door.

In testimony whereof I affix my signature in the presence of two witnesses.

MARCUS GARFINKEL.

Witnesses:

ANNA M. DORR,
KARL H. BUTLER.
